UNITED STATES PATENT OFFICE.

PAUL PARKES LLEWELLYN, OF CHICAGO, ILLINOIS, ASSIGNOR TO INTERSTATE IRON AND STEEL COMPANY, OF CHICAGO, ILLINOIS, A CORPORATION OF ILLINOIS.

RAILWAY-TIE PLATE.

1,184,363.

Specification of Letters Patent. Patented May 23, 1916.

Application filed November 5, 1915. Serial No. 59,715.

To all whom it may concern:

Be it known that I, PAUL P. LLEWELLYN, a citizen of the United States, residing at Chicago, in the county of Cook and State 5 of Illinois, have invented certain new and useful Improvements in Railway - Tie Plates, of which the following is a specification, reference being had therein to the accompanying drawing.

10 This invention relates to improvements in railway-tie plates and its object is to provide a tie-plate with oblique ribs or flanges on its under or tie-engaging face which will prevent both its creeping or moving across the tie under the longitudinal thrust or impact of the passing train, and also its spreading or slippage along the tie when subjected to lateral thrust or pressure of the car-wheel against the rail, as for example 15 when rounding a curve in the track.

By my invention tie-engaging flanges or ribs are provided on the underside of the plate extending obliquely of the line of the superposed rail so as to prevent both lateral 20 spreading and longitudinal creeping of the plates and rails upon the ties, and in my invention these oblique ribs or flanges are arranged in rows of parallel lines extending in different directions from the median line 25 of the plate to its opposite sides with each pair of opposite ribs forming a wedge which extends across the line of the rail and whose apex is directed toward the center of the track, as shown for example in Figure 2.

30 In the accompanying drawings, Fig. 1 is a top plan view of a section of a railway rail with one of my tie-plates; Fig. 2 is a bottom plan view of the tie plate, and Fig. 3 is a longitudinal sectional view of the 35 plate on the line 3—3 of Fig. 2 looking in the direction of the arrows.

In constructing a tie-plate in accordance with my invention, the metallic plate designated as a whole by the reference letter A is 40 of rectangular shape of any suitable or desired dimensions, and is formed with spike holes a properly located to receive spikes B to secure the rail C to the underlying tie. The plate is provided near one end with an 45 upwardly extending shoulder or abutment a' on its upper face to prevent buckling of the plate under the weight of the passing train and to hold the rail-flange from spreading on the plate, it being understood 50 that in practice the end of the plate near 55 which the abutment a' is arranged is usually the outer end of the plate with reference to the track itself.

On the under or tie-side of the plate I provide a plurality of flanges or ribs a² 60 adapted to be embedded in the wood of the associated tie and arranged obliquely of the length of the plate so that they are oblique to the line of the superposed rail when the plates are assembled in place between the 65 rail and ties. By this oblique arrangement of the ribs the latter afford an effective resistance to both the longitudinal and lateral thrusts of passing trains and prevent the plates from spreading along the length of 70 the ties and from creeping across the ties in the line of the rail. The diagonal ribs are arranged in rows of parallel lines which extend in different directions from the longitudinal central line of the plate to its opposite sides with each pair of opposite ribs forming a wedge which extends across the line of the rail and whose apex is directed 75 toward the center of the track. This latter arrangement is illustrated in Fig. 2 of the 80 accompanying drawing. In practice I prefer that the apex or point of each wedge extending toward the inner end of the plate or center of the track joins and merges into a longitudinal rib a³ at the center or median 85 line of the plate so that each oblique rib holds the plate against creeping across the tie under longitudinal thrusts of the passing train, and also holds it against spreading toward the outer end of the tie due to lateral 90 thrusts of the train, as the oblique arrangement of the ribs enables them to resist movement of the plate in either direction. Also by having the opening between a pair of ribs forming a wedge face toward the 95 outer end of the plate, i. e., that end lying beyond or outside of the track itself, the spreading strain or pressure of the plate toward the outer end of the tie tends to compact the wood of the ties between the ribs 100 forming the wedge, thereby increasing the resistance of the ties to the spreading of the rails. This construction is of decided advantage because the ribs of each wedge thereby act to compact the wood of the tie 105 to increase its resistance to this lateral thrust of the plate, instead of splitting the tie or forcing its fibers apart and thereby decreasing its resistance to the lateral thrust of the plate as is the case when the apex of 110

the wedge points toward the outer end of the tie and so is forced into wedging engagement with the tie.

In practice I also prefer that the inner angle between the rows shall be such that the outer ends of each pair of ribs forming a wedge shall extend beyond the apex of the next pair, or stating the same arrangement in a different way that the apex of each pair shall lie inside the line extending across between the ends of the next pair. By this latter arrangement when the plates are cut from a strip or length of metal with the shear for the inner end of a plate at the apex of a pair of ribs, the shear for the outer end of the plate will cut through the ends of another pair of ribs and thus leave at the inner edge of each plate a pair of short oblique ribs α^2 located at a point where the weight and pressure of the car-wheels tend most to impact the plates on the ties, so that I obtain the resistance of these short ribs against movement of the plates more effectually than if they were located at the outer end of the plate in extension of the last pair of ribs at that end. If desired a plurality of longitudinally extending ribs α^3 may be employed, parallel with the median line of the plate, and one at each side of the plate.

I claim:—

1. A railway-tie plate provided on its under side with a central longitudinal rib and a plurality of ribs arranged in rows of parallel lines extending in different directions from the median rib of the plate to its opposite sides with each pair of opposite ribs in the form of a wedge having its apex extend-

ing transversely to the line of the associated rail and toward the inner end of the plate.

2. A railway-tie plate provided on its under side with a plurality of tie-engaging ribs arranged in rows of parallel lines extending in different directions from the median line of the plate to its opposite sides with each pair of opposite ribs in the form of a wedge having its apex extending transversely to the line of the associated rail and toward the center of the track.

3. A railway-tie plate provided on its under side with a plurality of tie-engaging ribs extending longitudinally of the plate at its center and sides and with a plurality of tie-engaging ribs extending obliquely of the plate in rows of parallel lines from the median rib to the side ribs with each pair of opposite oblique ribs in the form of a wedge opening toward the outer end of the plate.

4. A railway-tie plate provided on its under side with a plurality of tie-engaging ribs arranged in rows of parallel lines extending in different directions from the median line of the plate to its opposite sides with each pair of opposite ribs in the form of a wedge having its apex extending transversely to the line of the associated rail and toward the center of the track, and with a rib at each of its inner corners parallel with the other ribs on its side of said median line.

In testimony whereof I affix my signature in presence of two witnesses.

PAUL PARKES LLEWELLYN.
